5 Claims. (Cl. 260—309)

Matter enclosed in heavy brackets [ ] appears in the original patent but forms no part of this reissue specification; matter printed in italics indicates the additions made by reissue.

This invention comprises new anti-thyroid compounds. It is known that 1-methyl-2-mercaptopglyoxaline is a very potent anti-thyroid agent. Its activity is much greater than thiouracil, the drug in most common use.

The new compounds of the present invention [have the formula] have one of the two following formulae:

which R is an alkyl, aryl or alkaryl group and R' is an alkoxy, alkylamino or aralkyloxy group, or mercaptoglyoxaline residue.

These compounds are no less potent than 1-methyl-2-mercaptopglyoxaline and have the advantage of being relatively tasteless and of having a more prolonged action. In these respects, the compounds hereinafter described in the examples are particularly valuable. They exhibit no evidence of toxicity.

The compounds may be produced from 2-mercaptopglyoxalines having a substituent group R on the 1-nitrogen atom, according to the following reaction.

The R-substituted 2-mercaptopglyoxalines themselves are prepared by either of the two following methods which are already known.

(a) By the reaction of bromoacetal under pressure with an amine (e. g. methylamine, allylamine, benzylamine, aniline, or cinnamylamine) followed by ring closure with an alkali thiocyanate in acid solution, or (b) the reaction in alcoholic solution of aminoacetal with organic isothiocyanate (e. g. methylisothiocyanate, allylisothiocyanate, benzylisothiocyanate, or phenylisothiocyanate) followed, if necessary, by treatment of the formed substituted thiourea with acid to effect ring closure.

The following examples are given in illustration:

Example 1.—Preparation of 1-methyl-[2]-3-carbethoxy thioglyoxaline-[2]-2-thioglyoxalone

0.1 mol. of 1-methyl-2-mercaptopglyoxaline is dissolved

in the minimum quantity of pyridine at 0° C. 0.1 mol. of ethyl chloroformate is added dropwise with stirring. More pyridine is added, if necessary, to keep the mixture semi-fluid. The sludge is then placed in an ice-box for 30 minutes. The crystals are filtered off and washed firstly with a little ethanol and secondly with ethanol and water. The product is crystallised from the solvent to give colourless needles having a melting point of 122–3° C. Found: C, 45.7; H, 5.4. C₇H₁₀O₂N₂S requires C, 45.2; H, 5.4%.

Example 2.—Preparation of 1-methyl-[2]-3-carbethoxy thioglyoxaline-[2]-2-thioglyoxalone

The procedure of Example 1 is followed but substituting methyl chloroformate for the ethyl ester. The product, recrystallised from ethanol, has a melting point of 135° C. Found: C, 41.7; H, 4.4. C₆H₈O₂N₂S requires C, 41.8; H, 4.6%.

Example 3.—Preparation of 1-methyl-[2]-3-carbobenzoxy thioglyoxaline-[2]-2-thioglyoxalone

(a) 0.1 mol of 1-methyl-2-mercaptopglyoxaline is dissolved in the minimum amount of pyridine at 0° C. 0.1 mol of carbobenzoxy chloride is added dropwise with stirring. The solution is then stirred for ½–1 hour at room-temperature and placed in a vacuum desiccator over concentrated H₂SO₄/KOH.

The sticky oil is rubbed under petroleum-ether and the solvent poured off. This is repeated twice. The thick oil is then rubbed under water which causes it to crystallise slowly. The white crystalline material is filtered off. On recrystallisation from benzene/petroleum-ether (60–80 C.) the product is obtained in white needles having a melting point of 91–92° C. (b) 0.1 mol of 1-methyl-2-mercaptopglyoxaline is dissolved in 50 ml. of 4 N-caustic soda at 0° C. 0.1 mol. of carbobenzoxy chloride is added slowly. After the addition, the mixture is stirred at 0° C. for 15–30 minutes. The reaction mixture is then placed in an icebox for ½ hour, the white solid filtered off and washed firstly with water and secondly with petroleum-ether. The solid is crystallised from benzene/petroleum-ether to give white needles having a melting point of 91–92° C. Found: C, 58.3; H, 4.9. C₁₂H₁₂O₂N₂S requires C, 58.1; H, 4.9%.

Example 4.—Preparation of 1-methyl-[2]-3-hippuroyl thioglyoxaline-[2]-2-thioglyoxalone

0.01 mol. of 1-methyl-2-mercaptopglyoxaline is dissolved in 10 ml. β-picoline at room temperature and 0.01 mol. 2-phenyloxazol-5-one added slowly. The mixture is allowed to stand at room temperature for 24 hrs., and then is poured into ice water with stirring. The small crystals appearing are then removed by filtration and recrystallised several times from ethyl acetate in which they are rather sparingly soluble. This gives a colourless microcrystalline product, M. P. 175° C. Found C, 56.4; H, 4.9; N, 15.3%. C₁₃H₁₃O₂N₃S requires C, 56.9; H, 4.7; N, 15.3%.

Example 5.—Preparation of di-(1-methyl-2-glyoxaliny) dithiocarbonate dihydrochloride

0.01 mol. of 1-methyl-2-mercaptopglyoxaline is dissolved in 30 ml. dry benzene and 0.01 mol. phosgene dissolved in toluene is added slowly with cooling. The reddish coloured precipitate is filtered off and recrystallised from alcohol containing a small amount of water. Colourless needles M. P. 167° C. Found: C, 32.3; H, 4.1%. C₉H₁₂ON₄S₂Cl₂H₂O requires C, 31.4; H, 4.07%.

We claim:

1. As a new anti-thyroid compound, a substance selected from the group consisting of 1-methyl-2-carbethoxy thioglyoxaline, 1-methyl-2-carbomethoxy thioglyoxaline,

1-methyl-2-carbobenzoxy thioglyoxaline, 1-methyl-2-hipuroyl-thioglyoxaline and di-(1-methyl-2-glyoxaliny) di-thiolcarbonate dihydrochloride.]

【2. As a new anti-thyroid compound, the substance 1-methyl-2-carbethoxythioglyoxaline.]

【3. As a new anti-thyroid compound, the substance 1-methyl-2-carbomethoxythioglyoxaline.]

【4. As a new anti-thyroid compound, the substance 1-methyl-2-carbobenzoxythioglyoxaline.]

【5. As a new anti-thyroid compound, the substance 1-methyl-2-hippurylthioglyoxaline.]

【6. As a new anti-thyroid compound, the substance di-(1-methyl-2-glyoxaliny) di-thiolcarbonate dihydrochloride.]

7. The product resulting from the process of producing antithyroid compounds by reacting 2-mercaptop glyoxaline having a substituent methyl radical R on the 1-nitrogen atom with a compound selected from the group consisting of ClCOCl and ClCOR' where R' is selected from the group consisting of lower alkyl, benzyl, and mercaptoglyoxaliny radicals, in the presence of a tertiary base.

8. The product resulting from the process of producing an antithyroid compound by reacting 1-methyl-2-mercaptopglyoxaline with ethyl chloroformate while cool-

ing in the presence of a tertiary base and recovering the reaction product produced.

9. The product resulting from the process of producing an antithyroid compound by reacting while cooling 1-methyl-2-mercaptopglyoxaline with methyl chloroformate in the presence of a tertiary base and recovering the reaction product formed.

10. The product resulting from the process of producing an antithyroid compound by reacting while cooling 1-methyl-2-mercaptopglyoxaline with carbobenzoxy chloride in the presence of a tertiary base and recovering the reaction product formed.

11. The product resulting from the process of producing an antithyroid compound by reacting while cooling 1-methyl-2-mercaptopglyoxaline with phosgene, in the presence of a tertiary base and recovering the reaction product formed
